UNITED STATES PATENT OFFICE.

JULIUS FRANKENBERG, OF MILWAUKEE, WISCONSIN.

FLUID-GAS COMPRESSOR.

Original application filed July 1, 1920, Serial No. 393,390. Divided and this application filed September 13, 1924. Serial No. 737,566.

This is a divisional application of my co-pending application Serial Number 393,390, filed the 1st day of July, 1920, for improvements in domestic refrigerating units, and relates to improvements in fluid gas compressors, to be used for any purpose or in connection with any kind of apparatus to which it may be found adaptable or applicable, but particularly for use and in connection with refrigerating apparatus using anhydrous ammonia or any other kindred refrigerant, which type of apparatus is so well understood by those skilled in the art to which the invention pertains, as to require no illustration herein, but which will be referred to in a general way.

The invention consists in certain peculiarities of the construction, novel arrangement, combination and cooperation of the various parts thereof, as will be hereinafter more fully set forth and specifically claimed.

The principal object of the invention is to produce a compact fluid gas compressor for use in meat markets and down to the domestic sizes, which embodies maximum efficiency, minimum weight, and minimum general displacement combined with unusual reliability and endurance of its component parts.

The only possible way to attain this object is to employ high speed operation which makes special valve design or construction a necessity. Especially is this true as to the suction valve of the compressor, as high speed generally reduces the latter's volumetric efficiency, a disadvantage obviated in my device. Since most refrigerating machines use anhydrous ammonia, the ammonia type compressor will be hereinafter more fully described, in preference to the sulphur-dioxide type of compressor, although a form of the invention for the last named type of compressor will also be described, which descriptions will be more readily understood when read in conjunction with the accompanying drawings, in which embodiments of which the invention is susceptible is illustrated; it being understood that changes and modifications may be resorted to without a departure from the spirit or essence of the invention, so long as they fall within the scope of the appended claims forming a part hereof.

In the accompanying drawings,—

Fig. 1 is a central vertical sectional view 55 of the compressor cylinder with the piston and the compressor valves in place.

Fig. 2 is an enlarged view partly in section and partly in elevation of the upper portion of the piston, more clearly showing 60 the construction and arrangement of the suction valve and its co-operating parts.

Fig. 3 is a plan view partly in section taken on line 3—3 of Fig. 1 as indicated by the arrows.

Fig. 4 is a horizontal sectional view taken on line 4—4 of Fig. 1 showing a portion of the suction plate valve broken away.

Fig. 5 is a detached perspective view of the discharge valve.

Fig. 6 is a central vertical section of modified forms of the compressor cylinder, the piston and valves showing the lower portion of the discharge hood for use in connection with sulphur dioxide or similar refrigerating apparatus, and

Fig. 7 is a top plan view of said cylinder head and discharge valve with the hood omitted.

Like numerals of reference refer to corresponding parts throughout the different views of the drawings.

Referring now more particularly to Figs. 1 to 5 inclusive of the drawings, the compressor cylinder is designated as a whole by 85 the numeral 10 and said cylinder has at its lower end a horizontally disposed flange 11 adapted to be bolted or secured to the top of a crank case, not shown, of an ammonia compressor, preferably, of the enclosed vertical type, which type and which arrangement is now so well known that it is deemed unnecessary to illustrate or more fully explain the mounting of the cylinder.

As shown, the cylinder 10 is equipped 95 with a piston, designated as an entirety by the numeral 12 for vertical operation in the bore of the cylinder, which piston has its lower end connected to the crank shaft by means of a connecting rod 13 in the ordinary or any well known way. The piston 12 is of the well known double trunk type and is so arranged with respect to the bore of the cylinder that in its reciprocation therein it will consecutively open and close ports 17 and 18 leading from an annular gas cham-

ber 14 to the cavity of the cylinder, with which ports and chamber the cylinder is provided at a suitable point below its upper end. The chamber 14 has communication 5 through an opening 16 with a supply of gas, not shown.

The upper portion of the cylinder 10 is provided with an annular chamber 15 to act as a water jacket in a well known way. The 10 upper end of the piston 12 is provided with a vertical opening in which is seated the upper end of a guide or sleeve 25 for a valve stem 21 which has on its lower end a head 21^a normally held in spaced relation 15 with respect to the sleeve or guide 25 by means of a relatively light spring 23 encircling said guide and resting at one of its ends on the head or enlargement 21^a and at its other end against the lower surface of 20 the top of the piston as will be readily understood by reference to Fig. 1 of the drawings. The sleeve or guide 25 has its upper end flush with the upper end of the piston 12 and may be riveted or otherwise secured 25 in place. The upper surface of the piston 12 is provided with an annular groove or port 26 which is concentric with respect to the sleeve 25.

Formed in the upper end of the piston 30 are a plurality of spaced ports 19 arranged in a circle and registering or communicating at their upper ends with the port 26. Between the port or annular groove 26 and the guide 25 the upper surface of the upper 35 end of the piston is provided with an annular groove or channel 26^a for the purpose to be presently explained. Loosely mounted around the upper portion of the stem 21 is the suction valve 20 which is by 40 preference circular in shape and of such dimensions as to cover almost the entire top of the piston 12 as shown in Figs. 1, 2 and 4 of the drawings. This valve 20 by preference is made of very thin spring steel and 45 is loosely held around the stem 21 by means of a knob or head 22 rigidly secured on the upper end of the stem 21. This knob or enlargement 22 has its surface adjacent the valve 20 outwardly and upwardly extended 50 or shaped, while its upper lateral portion is upwardly and inwardly extended or shaped so that flexing movement of the valve 20 will not be materially interfered with thereby and so that when the piston is at the uppermost position, the knob or head 22 will fit in or co-operate with an opening in an element of the compressor located in the upper portion of the cylinder.

The efficient action of the valve 20 is based, 60 firstly, upon its great flexibility, it being made of very thin steel especially adapted for the purpose, and being of comparatively large diameter; secondly, upon the fact that it is not held solidly in the center, it having 65 a loose fit around the stem 21 as clearly

shown in Fig. 2, and is there yieldingly held by means of the stem 21, knob 22 and the spring 23. By my improvements other advantages are attained; for instance, supposing the piston 12 is at its extreme upper 70 position. On its return or downward stroke, the valve stem 21 with the knob 22, by virtue of their inertia, will tend to remain stationary, and hence will lag behind the piston, thus relieving the pressure between the knob 75 22 and the plate valve 20 exerted by the spring 23. The lag of the stem 21 resulting from the bodily shifting of the stem 21 with respect to the piston, as above indicated, also permits bodily shifting or lifting of the 80 plate valve 20 away from the end of the piston. In addition, as the suction gas rushes through the ports 19 and annular port 26, it causes the plate valve 20 to flex about the knob 22^a. The amount of flexing, 85 however, will obviously be less than in those types of valves where a spring plate is securely fastened to the piston. Hence, the bodily lifting of the plate valve or bodily separation from the piston, combined with 90 the relatively small amount of flexing of the valve promotes long life of the suction plate valve while at the same time the area of the passages for the transference of the suction gases is relatively large, thus promoting increased volumetric efficiency of the compressor and particularly in a high speed type of compressor with which my invention is more particularly concerned. The amount of lift 95 or bodily separation of the plate valve 20 from the piston head is limited by the amount of bodily shifting of the stem 21, as will be obvious and this amount may be regulated to a predetermined degree, as will be apparent to those skilled in the art. 100 While the degree of separation of the plate valve 20 is limited by the knob 22 of the stem 21, this in no wise interferes with the instantaneous proper seating of the plate valve to close the ports immediately upon the 105 beginning of the up or compression stroke of the piston.

As the suction and discharge pipes of ammonia compressors are kept as small as possible, for well known reasons, means 110 must be provided for high speed operation to prevent drop in the suction pressure other than having an efficient suction valve. This is most effectively accomplished by providing the cylinder 10 with the gas receiving 115 chamber 14 and the two suction ports 17 and 18 which are always in communication consecutively with the space formed by the two ends of the piston. If only one of these ports were provided, as is usually done in 120 the enclosed type compressor, the piston 12 would necessarily be very long, which is a mechanical disadvantage, the increased weight of the piston making it so much more difficult to balance the reciprocating parts 125 130

of the compressor, especially for high speed operation and single piston types.

In the type of the compressor now under consideration it will be seen that the upper portion of the bore or cavity of the cylinder 10 is considerably enlarged annularly and that the upper portion of the smaller part of said bore or cavity is surrounded by a conical upward extension 31, upon which is mounted a safety head 29 having centrally therein a discharge port 35 of such form as to correspond to the shape of the upper portion of the knob 22 of the suction valve mechanism. The upper edge of the port 35 is provided with a rib 35^a preferably produced by forming a depression or comparatively wide groove 35^b concentrically around the port 35 in the upper surface of said safety head. This circular rib 35^a provides a valve seat for the discharge valve 27 which consists of an elongated strip of thin flexible steel, and is mounted at one of its ends on the head 29, and so as to cover and rest on the seat 35^a around the port 35 near its other end. Another but shorter strip 28 of flexible steel is mounted on and in coincidence with the valve 27, but terminates at one of its ends short of the corresponding end of the valve 27 as is clearly shown in Figs. 1 and 3 of the drawings. Both the valve 27 and the reinforcing or cover member 28 are tightly clamped at their end portions located at the periphery of the head 29, between said head and the valve guard 30, by screws 32 extended through openings in said guard and engaging said head. The guard 30 is provided on its lower surface directly above the port 35 with an upwardly curved portion 36 the greater part of which curved portion is out of contact with the auxiliary reinforcing member 28, which construction will permit the discharge valve and the member 28 to be bent against the curved portion 36, thus assisting in the quick seating of the valve 27. The entire discharge valve mechanism is held rigidly upon the top of the rib or projection 31 by means of the coiled spring 33, which is compressed between the cylinder head 34 and the valve guard 30, the projections 38 and 39 on the said head and guard respectively serving to hold and centralize the action of said spring.

The modified construction illustrated in Figs. 6 and 7, of the drawings, embodies features which are more particularly applicable for use in connection with a sulphur dioxide compressor, and are somewhat similar to those used in an ammonia compressor, except, that an ordinary single trunk piston 12^a, is employed in the modified form of the cylinder 10^a instead of the double trunk piston of the first described construction, and that the gas receiving chamber 14, of the former construction is omitted, for the

reason, that in the sulphur dioxide machines the suction pipe leads directly into the crank-case of said machine, to which case the cylinder 10^a has its horizontal flange 11^a bolted or secured. Besides, it will be noted that the bore or cavity of the modified form of the cylinder 10^a has the annular enlargement at the upper end of the cavity of the other construction omitted, or in other words, is of the same size throughout its entire length. Furthermore, that the modified form of the guard 30^a, for the discharge valve 27 and reinforcing or cover member 28, is T-shaped instead of the form of the guard of the other construction. However, the guard 30^a, serves to clamp the members 27 and 28 between it and the head 29^a, which in the modification forms the cylinder head on which is mounted the hood 50, employed for a well known purpose. The guard 30^a has the lower surface of its stem, or that portion thereof extended over the port 35, curved upward as in the other construction and for the same purpose. Otherwise, the elements of the modification are substantially the same as that of the first described construction.

Having thus fully described my invention, what I claim as new and desire to secure by Letters Patent is:

1. A vertical type fluid gas compressor, including in combination with a cylinder having near the upper end of its bore or cavity an upwardly tapered projection forming a narrow concentric valve seat, of a safety head resting upon said seat of the cylinder, said safety head having a depending tapered concentric projection fitting removably upon the said valve seat, a discharge port in said safety head concentric with the cylinder and said head, said discharge port terminating at its upper end in a narrow concentric valve seat, an elongated thin flexible plate valve covering the last named valve seat, at least one flexible thin steel plate covering a portion of said elongated plate valve to reinforce the same, a guard member secured to said safety head and clamping the outer ends of said plate valve and said reinforcing member between said guard member and said safety head, said guard member having a curved portion located above but spaced from said plate valve and said reinforcing member to limit the lift of said valve and to provide proper tension for the same, and a heavy coil spring between said guard member and the cylinder head to hold the entire discharge valve mechanism upon the said tapered projection of the cylinder.

2. In a vertical type fluid gas compressor, the combination with a cylinder having near the upper end of its bore or cavity an upwardly tapered projection forming a narrow concentric valve seat, of a safety head

resting upon said seat of the cylinder, said safety head having a depending tapered concentric projection fitting removably upon the said valve seat, a discharge port in said safety head concentric with the cylinder and said head, said discharge port terminating at its upper end in a narrow concentric valve seat, an elongated thin flexible plate valve covering the last named valve seat, at least one flexible thin steel plate covering a portion of said elongated plate valve to reinforce the same, a guard member secured to said safety head and clamping the outer ends of said plate valve and said reinforcing member between said guard member and said safety head, said guard member having a curved portion located above but spaced from said plate valve and said reinforcing member to limit the lift of said valve and to provide proper tension for the same, a heavy coil spring between said guard member and the cylinder head to hold the entire discharge valve mechanism upon the said tapered projection of the cylinder, a piston operatively located in said cylinder and having a cavity, said cylinder provided in the face of one of its ends with a plurality of suction ports, a thin flexible plate valve seated on the face of the piston and covering said ports, a valve stem centrally and movably located in said valve plate and piston end and having at its outer end a knob holding said valve plate upon its seat, said knob being tapered on its lower surface to facilitate the flexibility of said plate valve, said knob being tapered on its upper surface to fit in the discharge port of said safety head, a guide for said stem located centrally in said end of the piston and extended through said plate valve, a head on the lower end of said stem for the purpose of limiting the lift of said valve plate, and a coil spring surrounding said stem between its said head and the aforesaid end of the piston to flexibly hold the plate valve upon its seat.

3. A reciprocating piston for a compressor cylinder, said piston including, a head provided with a suction port; a thin flexible plate valve normally positioned against the end of said piston to close said port, said plate valve being bodily shiftable away from said head as well as flexible; and means, carried by the piston head, for normally retaining said plate valve in said normal position, said means including, an element bodily shiftable, within predetermined limits, with respect to the piston head, to thereby permit the bodily separation of the plate valve from the head and flexing thereof to uncover said port during a return stroke of the piston.

4. In combination, a reciprocating piston having the head thereof ported; a flexible plate valve adapted to close said ported head; and means, carried by the piston head

for retaining said plate valve in operative relation with the piston head, said means permitting a limited bodily separation of the plate valve from the piston head in addition to the flexing of the plate valve.

5. A reciprocating piston having the head thereof ported; a spring-influenced and inertia-controlled element mounted on the piston head and adapted for limited movement with respect thereto; and a flexible plate valve adapted to close and uncover said ported head, said plate valve being retained in operative relation to the piston head by said element, said plate valve being both bodily shiftable relatively to said head and also flexible about said element to uncover the ported head upon a return stroke of the piston.

6. In combination, a piston having a plurality of suction ports therein, a flexible plate valve carried by the piston and adapted to close said ports, said plate valve being bodily shiftable with respect to the piston to uncover said ports; and means, carried by the piston, co-operable with said plate valve to permit bodily shift of said plate valve to uncover said ports, said means including an element having a section of lesser area than that of the plate valve and about which the plate valve is adapted to flex when the ports are uncovered.

7. In combination, a reciprocating piston having a plurality of suction ports therein; a flexible plate valve carried by said piston and adapted to close said ports during a compression stroke; and an inertia-controlled element also carried by said piston, said plate valve and element being each adapted for movement relatively to the piston independent of each other, said element limiting the opening movement of said plate valve and the latter being adapted to flex about said element.

8. In combination, a reciprocating piston having a plurality of suction ports therein; a flexible plate valve carried by said piston and adapted to close said ports during a compression stroke; and an inertia-controlled element also carried by said piston, said plate valve and element being each adapted for movement relatively to the piston independent of each other, said element limiting the opening movement of said plate valve and the latter being adapted to flex about said element, said plate valve being in the form of a disc, centrally perforated and said element having a stem extending loosely through the perforation.

9. A reciprocating piston for a compressor cylinder said piston including: a head having a plurality of ports therein; a flexible plate valve loosely mounted on the end of said head and adapted to cover said ports, said plate valve being centrally perforated; a stem mounted to slide axially of the piston

for a limited amount, said stem being headed at each end and the stem passing through the perforation of said plate valve, the head on the adjacent end of the stem serving to, 5 retain the plate valve in operative relation with the piston head and the plate valve being flexible about said head of the stem; and relatively light spring means, interposed between the piston head and the other

head of the stem, normally tending to influence said stem in a direction to seat the plate valve against the piston head, the inertia of said stem being sufficient, on a return stroke, to overcome the spring influence to thereby permit bodily shifting of the 10 stem and of the plate valve relatively to the piston head to uncover the ports thereof. 15

JULIUS FRANKENBERG.
